UNITED STATES PATENT OFFICE

WELCOME CARPENTER DENNIS, OF OAKLAND, CALIFORNIA

SHIP GOVERNOR

Application filed March 8, 1930. Serial No. 434,406.

This invention relates to governors for preventing racing of the engine on a boat in rough seas when the stern of the boat rises so as to lift the propeller partially out of the water.

An object of the invention is to provide a device for this purpose which will be thoroughly reliable and simple in construction and operation.

Referring to the accompanying drawings, which are made a part hereof and on which similar reference characters indicate similar parts,

Figure 1 is a side elevation of the device with parts shown in section,

Figure 2, a plan view, and

Figure 3, a section on line 3—3 of Figure 1.

In the drawings numeral 10 indicates a plate which may be secured to any fixed part 20 of the boat. This plate has a pair of lugs 11 for receiving a pivot rod 12 on which depending lugs 13 are pivoted. The lugs 13 are secured to the under side of the base 14 of a box 15. Adjusting screws 16 may be 25 threaded through lugs 17 on the ends of the plate 4 and locked there so as to pivot the plate 14 and lock it in any desired position with respect to the plate 10. Secured to the bottom 14 of the box 15 is a plate 18 having 30 upturned edges 19 to provide a track for a roller 20. The roller is provided with grooves 21 for engaging the tracks 19 to guide the roller as it rolls forward or backward due to pitching of the ship. The roller 35 20 has a shaft 22 which may be a small rod or other shaft to which is attached a rod 23 which rod at its other end is attached to an arm 24 for controlling a valve 25. The end of the rod 23 may engage in one of a number 40 of holes 26 to limit the throw of the valve arm 24. The extent to which the valve is opened determines the quickness with which the engine responds in change of speed. With some sizes of boats for which this device is designed, when the rod 23 is secured 45 in the outer hole 26 the change of speed of the engine will occur in six seconds. When the rod is in the next hole the change takes place in five seconds. When it is in the next or in the inner hole the change occurs

in four and three seconds respectively. The valve 25 may be any valve for controlling the speed of the ship's engine, as for example the main throttle valve or a butterfly valve. The plate 18 may be secured to the 55 bottom 14 of the box by means of bolts 27. A strap 28 may be secured at one end to the top of the plate 18 by means of one of the belts 27 and may be bent around and rest at its other end against the inner end of the 60 box 15. The strap 28 serves as a stop abutment for the roll 20.

In operation the box 15 is adjusted by means of the screws 16 so that the plate 14 will be level or so as to maintain the throttle 65 25 open when the ship is in a level position. When the ship pitches due to rough seas and the stern rises out of the water the propeller, relieved of its load will have a tendency to permit the engine to race. As the stern rises, however, the roll 20 will move forward and close the throttle 25 to reduce the speed of the engine at this time. When the stern settles 70 back into the water again the roll 20 will be returned to its rear position, as shown in Figure 1 to open the throttle again to admit motive fluid to the engine. The engine, shown as a whole at numeral 29, may be any motive fluid engine which is operated either by steam or by vacuum. Obviously the 75 throttle valve 25 may be in control of any motor, as for example, instead of a fluid motor the whole valve assembly might be a rheostat operated by an arm 24 to control the speed 80 of an electric motor.

It will be obvious to those skilled in the art that various changes may be made in my device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. Control means for a marine engine comprising a valve, a valve arm operatively connected to said valve, a box adjustably positioned upon a ship, a pair of tracks secured within said box, a roll mounted upon said

tracks, a shaft extending through the center of said roll, a rod integrally connected to said shaft for maintaining said shaft at a fixed distance relative to said valve arm 5 whereby any movement of said roll will operate said valve, substantially as set forth.

2. A ship's governor comprising in combination, a motor, a motor control valve having a control arm extending therefrom, a box 10 adjustably positioned upon a ship, a pair of tracks secured within said box, a roll having grooves in its periphery mounted on said tracks, a rod pivotally connected at one end to said control arm and at the other end to the center of said roll whereby any movement of said roll will actuate said valve, substantially as set forth.

3. A ship's governor comprising in combination with a marine engine, a control valve 20 having a control arm extending therefrom, a housing adjustably mounted on a ship, tracks secured in said housing, a roll provided with a centered shaft adapted to be mounted on said tracks, a rod integrally connected at one 25 end to said shaft and adjustably connected at the other end to said control arm whereby any movement of said roll is positively transmitted to said control valve, and means for cushioning the impact of said roll within 30 the box at the limit of its movement in one direction, substantially as set forth.

In witness whereof, I have hereunto set my hand at Oakland, California, this 28th day of February, A. D. nineteen hundred and 35 thirty.

WELCOME CARPENTER DENNIS.
